GEARED PUMP HEAD FOR WATER WELLS

Andrew J. Richardson, Lubbock, Tex.

Application June 1, 1951, Serial No. 229,385

4 Claims. (Cl. 103—83)

1

This invention relates to pumping equipment for water wells, and it has particular reference to pump heads for turbine type water pumps, and its principal object resides in the provision of a gear head which is formed with a water passage capable of being concentrically connected to a well casing and an outlet or discharge pipe, and providing for an adjacent gear chamber for driving the pump to be cooled by water flowing through the flow passage.

Another object of the invention is that of providing a pump head which is compact in form and economical in operation and installation, affording a mechanism by which a greater volume of water can be produced at lesser costs, and by which much lighter materials can be employed in the production of the device insuring greater economy in manufacture without sacrificing durability and longevity.

A still further object of the invention resides in the provision of a pump head which can be readily connected to a well casing and has means formed therewith adapting the same to be attached to a discharge conduit for a flow line, or to an overhead storage, and providing for the removable installation of a rotary or turbine type pump in the casing at any desired level, and thus avoid the necessity for a fluid column to be maintained in the well.

It is also an object of the invention to provide a gear head for rotary type water pumps in which is defined a gear chamber for operating gears for the rotary pump in which the gears can operate in an oil bath and water cooled by the well liquids flowing in close proximity thereto, and further, to afford a means for readily changing the ratio between the driving and driven gears whereby prime movers of different R. P. M. can be employed without varying the R. P. M. of the pump shaft.

Broadly, the invention contemplates the provision of a simplified geared-head for rotary type water pumps whereby water from a cased well can be economically produced in suitable volume, and whereby the maintenance and operating costs can be substantially minimized.

While the foregoing objects are paramount, other and lesser objects will become manifest as the description proceeds, taken in connection with the appended drawings wherein:

Figure 1 is a vertical sectional view of the invention illustrating the arcuate flow passage in the head, the gear chamber, the pump unit removably supported in the well casing, and the pump shaft.

2

Figure 2 is a transverse sectional view, on lines 2—2 of Figure 1, showing the centering spiders for the pump shaft.

Figure 3 is an elevational view of an eccentric bearing plate for the drive shaft for the gear assembly.

Figure 4 is an elevational view of a concentric bearing plate, and

Figure 5 illustrates a modification of the pump supporting device including the composition seating ring, the casing being fragmentarily shown in vertical section.

A prime object of the invention is that of providing a gear head for operating the turbine pump which is connected directly to and forming a part of the discharge elbow which directs the flow of water from the vertical to horizontal, and eliminates the necessity for separate housing and extra lubricating devices, packing glands, and the like. By arranging the gear chamber is close proximity to the flow passage it is not necessary to provide any of the conventional types of cooling systems. Moreover, the device can be made more sturdy since its construction eliminates the necessity for a high foundation for the power unit.

Accordingly, the invention comprises a housing 10 which is formed with an arcuate water passage 11 therein which is actually a 90 degree turn. 30 The lower end of the housing 10 has an annular flange 12 thereon for connecting the same to the top of a well casing 13 by bolts 14, or other device. The opposite end of the portion of the housing forming the passage 11 also has an annular flange 15 by which the housing 10 is connected to a discharge conduit 16 by bolts 17, or the like.

The housing 10 is formed in one casting, and on the crown of the arcuate portion thereof is defined a gear chamber 18 which is separated from the passage 11 by a partition or inner wall 19 in which is provided an integral body 20 having a vertical bore 21 therethrough concentrically of the flanged lower end of the housing 10. 45 Above the body 20 is a circular opening 22 in the top 23 of the housing 10 and this opening is closed by a dome-shaped cap 24 whose peripheral flange is secured to the top 23 of the housing 10 by bolts 25. Interiorly of the cap 24 and centrally thereof is a boss 26 which provides a bearing for the upper end of a shaft 27 whose function will presently become manifest.

In the upper portion of the bore 21 of the body 20 is formed an annular cavity 28 into which is 50 extended the upper end of a tube 29 arranged

through the bore 21 and depending through the vertical leg of the housing 10 into the well casing 13. The upper end of the tube 29 is threaded interiorly and exteriorly and a flanged nut 30 is threaded on the end of the tube 29 within the cavity 28 against a packing gland 31 which embraces the shaft 27 which is arranged concentrically of the tube 29, a sleeve 32 being threaded internally of the upper end of the tube 29 to support the packing gland 31 beneath. The tube 29 is firmly secured in the bore 21 by a pair of nuts 33 threaded upon the tube 29 against the bottom of the body 20.

An annular recess 34 is formed in the top of the body 20 about the cavity 28 to receive a bearing race 35 for the bearing 36 arranged about the shaft 27 beneath a bevelled gear 37 thereon. Opposite the bearing 36, above the gear 37 is a pair of nuts 38 which are threaded upon the upper end of the shaft 27, the extreme upper end 39 being of reduced diameter to provide a spindle which is seated in the bearing 26, as previously described. A port 40 in the body 20 provides a communication between the gear chamber 18 and the cavity 28 whereby a lubricant, with which the chamber 18 is filled, can migrate into the cavity 28 to lubricate packing gland 31 about the shaft 27.

The shaft 27 may be of any desired length suitable for the proper operation of the pump unit 41 supported in the casing 13, and bearings 42 are spaced therealong within the tube 29 to concentrically support the shaft 27 therein. The pump unit 41 is supported in the casing 13 by either of the methods shown in Figures 1 and 5 and, as will become apparent from these illustrations it is removable from the well at will by pulling the shaft 27 and the tubing 29. This can be accomplished after the housing 10 has been disconnected from the casing 13.

The pump unit 41 is supported in the well casing 13 upon an annular bevelled seat 43 formed on a ring 44 of metal, or of some yieldable material, such as rubber or neoprene, which is secured at the proper depth between sections of the well casing 13 which are joined by a collar 45. When the ring 44 is of metal the joints can be welded, the ring 44 being welded to the sections. An annular plate 45' having a flared flange 46 thereon, is secured to the top or bottom of the pump unit 41 by bolts 47 to support the unit on the ring 44, the flared flange 46 of the ring being conformable to the bevelled seating surface thereof, as illustrated in Figures 1 and 5.

A suction pipe 48 depends from the pump unit 41 into the casing 13 and should be of such length as to extend into the water column therein whereby to flow the liquid into the upper casing above the seal provided around the seating ring 44. In this manner friction losses in moving the water to the surface are considerably minimized.

The bevelled gear 37 on the shaft 27 is meshed with a driving gear 49 fixed to the inner end of a drive shaft 50 of a power unit (not shown). The shaft 50 is journaled in a bearing 51 arranged in an annular recess 52 formed in a circular plate 53 on the outside of which is formed an integral sleeve 54 having a packing gland 55 and a follower 56 therein about the shaft 50 to provide a stuffing box therefor. The plate 53 is secured about its periphery to the housing 10 by bolts 57 and covers a circular opening 58 in the housing 10.

The plate 53, shown in Figure 1, has the sleeve

54 thereon eccentrically situated, as illustrated in greater detail in Figure 3, and for the purpose of affording driving gears of different diameters so that the ratios can be varied according to the 5 R. P. M. of the power unit. Figure 4 illustrates a plate 59, whose stuffing box is concentrically located, which is interchangeable with the plate 53 and can be secured by the bolts 57.

The pump shaft 27, which operates concentrically of the tube 29, is maintained centrally of the casing 13 by spider members 60 which have radial arms 61, as shown in Figures 1 and 2, and these members are secured on the tube 29 by threading or by welding, as desired, and serve 15 to guide the pump unit 41 to its seat on the ring 44 or upwardly through the well casing 13 when it is necessary to remove the pump unit or its drive shaft 27.

The arms 61 of the members 60 are preferably 20 of a somewhat yieldable character, such as malleable iron, so that these members will bend when irregularities occur in the casing wall as the assembly is moved through the casing 13. It will be noted that each of the arms 61 has 25 weakened portions 62 formed thereon so as to permit the arms to bend slightly when necessary.

It is contemplated that the gear chamber 18 be filled with a lubricant and thus the gears 37 and 49 are immersed in oil. The packing glands 31 and 55 are therefore quite necessary to seal the lubricant within the chamber 18 and the space about the shaft 27 within the cavity 28 fed by the port 40. A grease fitting 63 is threaded into the dome-shaped cap 24 and a small port 64 admits a lubricant therefrom to the upper end of the shaft 27.

Manifestly, the structure herein shown and described is capable of certain changes and modifications from time to time, by persons skilled in 40 the art, without departing from the spirit and intent of the invention or the scope of the appended claims.

What is claimed is:

1. In a geared head for a turbine water pump, in combination, a well casing having a rotary turbine pump supported therein, a housing formed with an arcuate water passage therethrough and having means formed therewith for connecting the same to said casing and to a discharge conduit having its axis at right angles to the axis of said casing, the said water passage having its axis concentric with the axis of said casing and the axis of said conduit, a gear chamber forming an integral part of the arcuate upper wall of said water passage, a rotary pump shaft connecting said rotary turbine pump with said gear chamber through said casing, a tubular casing surrounding said shaft, a driven gear on said shaft, and a driving gear meshed with said driven gear in said gear chamber for driving said shaft.

2. In a pump head for a turbine type of water pump, in combination, a well casing having a rotary pump removably supported therein, a discharge pipe arranged at right angles to the axis 65 of said casing, a housing having an arcuate water passage formed therein providing an uninterrupted axial communication between said casing and said discharge pipe, the said housing having a gear chamber formed therein above and adjacent to said passage, the inner wall of said 70 chamber conforming to the contour of said passage, a driven shaft arranged in said gear chamber and extending concentrically downwardly through said inner wall and a portion of said 75 passage and said casing to said pump, a tubular

casing surrounding said shaft, a driven bevel gear on said shaft in said chamber, and a driving bevel gear in said chamber meshed with said driven gear.

3. In a pumping apparatus for a water well, in combination, a well casing and a discharge conduit in right angular arrangement with respect to the axis of said casing, a rotary pump in said casing having a driven shaft arranged concentrically of said casing, a housing attached to the top of said casing and formed with a gear chamber and a curved water passage therein, the latter providing a substantially unobstructed axial communication between said well casing and said discharge conduit, the inner wall of said gear chamber defining an outer wall of said passage, a gear assembly enclosed in said gear chamber above said water passage and externally thereof for driving said shaft, the said gear assembly comprising a driven gear on said driven shaft and a driving gear meshed with said driven gear, and a tubular casing enclosing said shaft in said well casing.

4. In a pumping head for turbine type water pumps in a water well, in combination, a well casing in said well and a discharge conduit at

right angles to said casing, and a pump in said casing, a housing adapted for attachment to said well casing, the said housing having an arcuate water passage therethrough providing an axial communication between said casing and said discharge conduit in right angular arrangement, an integral portion of said housing defining a gear chamber above said water passage, a pump shaft in said chamber depending concentrically through a portion of said passage into said casing to said pump therein, a cylindrical housing for said shaft, a driven gear for said shaft on its upper end in said chamber, and a driving gear in said chamber arranged at right angles to said driven gear and in mesh therewith and having a shaft extending exteriorly of said chamber.
